[57] ABSTRACT

Described is a workpiece gage control system for a hot rolling mill, intended for use as an adjunct to existing gage control systems, which measures the temperature of incoming end of the workpieces and compares this with the temperature of the incoming end of the previous workpiece and the gage of the forward end of the previous workpiece. Assuming that a screwdown correction is required, this comparison results in a control signal which adjusts the screwdown setting of the mill to maintain output gage substantially constant regardless of temperature variations.

GAGE CONTROL SYSTEM FOR HOT ROLLING MILLS

This is a continuation of application, Ser. No. 715,051, filed Mar. 21, 1968, now abandoned.

BACKGROUND OF THE INVENTION

In hot rolling mills, such as bar mills, the incoming workpiece passes through a number of stands before its gage or thickness is measured as it emerges from the last stand. If the actual measured gage deviates from the desired gage, the screwdown settings of the various stands are adjusted, but by this time a considerable length of off-gage product has passed through the mill. The problem is complicated by the fact that regardless of the desired gage setting of the mill, the actual gage will vary with the temperature of the workpiece. That is, hotter, and consequently softer, workpieces will tend to be reduced to a greater degree than cooler workpieces.

Temperature variation from one workpiece to the next can result from various factors. For example, skid marks from the water cooled skids in the preheat furnace are a source of temperature variations. Also, the workpiece may be held up in the rolling schedule for a time long enough to cause the temperature to vary from bar-to-bar, and the spray at the descaler can cause the head of the workpiece to be colder or hotter than the body. This latter effect occurs since the body speed is controlled by the first stand speed; whereas the speed of the head is controlled by the approach table speed. Similarly, temperature variations occur due to differences between furnaces, and the speeds through which a pusher is moving the workpieces through the furnace. In short, it is exceedingly difficult to maintain all succeeding workpieces in a single order to have the same temperature characteristics.

SUMMARY OF THE INVENTION

As an overall object, the present invention provides a workpiece gage control system for a tandem hot rolling mill which senses temperature variations between successive workpieces and effects the desired control of workpiece gage by a change in the screwdown setting of the mill or in interstand tension or application of coolant or the like as a function of those temperature variations before the head end of the workpiece reaches the last stand of the mill.

More specifically, an object of the invention is to provide a control system of the type described which measures the temperature of a workpiece as it passes between the first and second stands of a tandem mill, and compares this temperature with the temperature of the previous workpiece and the actual gage of the previous workpiece to adjust the screwdown setting of the mill.

In accordance with the invention, a temperature measuring device is preferably positioned between the first and second stands of a tandem hot mill and arranged to measure the temperature of the head end of each workpiece passing through the mill. The measured temperature, expressed as an electrical signal, is applied to one of two integrators where it is stored until the head end of the next workpiece is fed into the mill. As the head end of this second workpiece enters the second stand of the mill, its temperature is also measured; and this measured temperature, again expressed

as an electrical signal, is applied to the other of the two integrators where it is stored. At the same time, the stored temperature of the head end of the workpiece is compared with (1) the temperature of the head end of the workpiece previously passing through the mill and (2) the gage of the head end of the workpiece previously rolled. Assuming that a screwdown correction is required, this comparison produces an error signal for adjusting the mill screwdown.

If, for example, the first workpiece is on gage, and the following workpiece is detected to be colder than the first, the mill screw will run down while the bar is in the mill to compensate for this deviation and give the bar a gage closer to the first one. If the head of the first bar is not on gage, an electrical signal proportional to the off-gage condition is compared with the temperatures of the first and second bars, respectively, to make the second workpiece on gage by the combination of the deviation of the first workpiece and the temperature variation.

Further, in accordance with the invention, the temperatures of the head ends of the workpieces are sampled for about 2 seconds, and these temperatures, in the form of electrical signals, are stored in the aforesaid integrators. However, such integrators will store the electrical signals proportional to temperature no longer than about 3 to 4 minutes. Accordingly, passage of the end of a given workpiece through the last stands in the tandem mill is recorded; and if no succeeding bar is passed through the mill within a period of 3 to 4 minutes, the temperatures comparison step is not made as before described. Rather, the screwdown is reset, and only a succeeding bar can be gaged by the temperature measurement system as described above.

The above and other objects and features of the invention will become apparent from the following detailed description taken in connection with the accompanying single FIGURE drawing which schematically illustrates one embodiment of the invention.

With reference now to the drawing, a tandem hot rolling mill is shown comprising a plurality of rolling mill stands S1-S6. A workpiece 10, heated to an elevated temperature, is shown passing through the stands S1-S6. As was explained above, the amount of reduction taken on the workpiece 10 and, hence, its issuing gage is a function of its temperature. For a given screwdown setting, a workpiece of a given temperature will be softer and its final gage less than that of a colder workpiece, assuming, of course, that they have the same metallurgical composition. As the strip issues from the last stand S6, its gage is measured by a thickness measuring X-ray gage 12, such as an X-ray gage. This gage is applied as an electrical signal to a screwdown control circuit 14 for the rolling mill; and is also fed to a head memory unit 16 which stores the gage of the forward end or head section only of the workpiece.

Once the workpiece 10 emerges from the last stand S6, its thickness can be measured by the gage 12 and the spacing between the rolls of the mill controlled by the conventional screwdown control circuit 14. However, by the time that the forward end of the strip reaches the gage 12, a considerable amount of material has passed through the mill which may be off-gage due to a difference in temperature from the preceding workpiece.

In accordance with the present invention, a temperature sensing or measuring device 18, such as an infrared pyrometer, is positioned between the first and second stands S1 and S2 of the mill and arranged to measure the temperature of the workpiece passing between these stands. The location between the first and second stands is chosen to eliminate the water spray at the entrance to the first stand. Also, the workpiece is cleaner of slag at this location, enabling better temperature readings. The measured temperature, as an electrical signal, is applied via lead 20 and resistor 21 to an isolation amplifier 22 having a resistive feedback path 23. The temperature measuring device 18 has a separate power supply, not shown, and the isolation amplifier has a high input impedance to match that of the device 18. The output of the isolation amplifier, in turn, can be applied through contacts CR2-A to a first integrator 24, or through a second set of contacts CR1-A to a second integrator 26. Each integrator 24 or 26 is provided with a feedback capacitor 28, the capacitor being in shunt with a circuit including a resistor 30 and normally open contacts CR2-B or CR1-B. As will be explained hereinafter, only one of the relays CR1 or CR2 is energized at any one time. When relay CR1, for example, is energized, the electrical signal proportional to the temperature of the strip is applied through isolation amplifier 22 to integrator 26. On the other hand, when relay CR2 is energized and relay CR1 deenergized, the electrical signal proportional to temperature is applied the integrator 24. All of the relays shown herein are preferably of the mercury wetted type, the symbols used in the drawing being for illustrative purposes only.

The output of amplifier 26 appears across resistor 32 and is applied via a movable tap 34, contacts CR3-A of relay CR3 and resistor 36 to the input of operational amplifier 38. Similarly, the output of integrator 24 appears across resistor 40 and is applied via movable tap 42, contacts CR5-A of relay CR5 and resistor 44 to the input of amplifier 38. Also applied to the input of amplifier 38 via contacts CR4-A of relay CR4 and resistor 46 is the electrical signal proportional to the temperature of the workpiece presently in the mill. That is, the signal applied through contacts CR4-A is that due to the temperature of the workpiece being rolled; whereas those from the integrators 24 or 26 are representative of the temperature of the workpiece next preceding the one being rolled.

Finally, the gage of the head of the previous workpiece rolled is applied from head memory unit 16 via lead 48, potentiometer 50, and resistor 52 to the input of operational amplifier 38. The signals applied to the input of amplifier 38 are thus compared; and its output appears across resistors 54 and 56; resistor 54 having a movable tap 58 thereon connected through a feedback resistor 60 to the input of the amplifier 38. The output from amplifier 38 appearing across resistors 54 and 56 is then applied to the screwdown control circuit 14.

In the operation of the system shown the drawing, and as will be explained hereinafter in detail, the relays CR1 and CR5, for example, will be energized momentarily, on the order of about 2 seconds, as soon as the forward end of a first workpiece being rolled enters the stand S2. At the same time, the relay CR4 will be energized to close its contacts CR4-A; however relays CR2 and CR3 will be deenergized. When the next succeed-

ing workpiece is rolled and its forward end reaches the stand S2, relays CR2 and CR3 will be energized momentarily, along with relay CR4 which is energized momentarily each time a workpiece enters stand S2. However, relays CR1 and CR5 will remain deenergized.

It can be seen, therefore, that as one workpiece is being rolled and relays CR1 and CR5 are energized, for example, the temperature of the workpiece being rolled is stored in integrator 26. When the next workpiece is rolled, however, relays CR2 and CR3 are energized. This permits storage of the temperature of the workpiece being rolled in integrator 24. At the same time, since contacts CR4-A are closed, the actual temperature of the workpiece now being rolled is compared with the temperature of the previous workpiece (i.e., that stored in integrator 26).

These temperatures are also compared with the head memory from storage circuit 16. Thus, assuming that the head of the previous workpiece was on gage, the electrical signal passing through contacts CR4-A and proportional to the temperature of the workpiece now being rolled is simply compared with that proportional to the temperature of the preceding workpiece passing through contacts CR3-A. If, however, the gage of the head of the previous workpiece was above or below the desired gage, the signal applied to the amplifier 38 is modified by the head memory signal. The signal passing through contacts CR4-A is compared in subtractive relationship with that passing through contacts CR3-A or CR5-A from the integrators, respectively. That is, if the signal proportional to the measured temperature of the workpiece passing through the mill is equal to that of the previous workpiece, then no corrective signal is sent to the screwdown control, assuming also that the output of the head memory unit 16 is zero, indicating that the actual gage of the preceding workpiece was equal to the desired gage as determined by the operator of the mill.

It now remains to be explained how the relays are actuated in the desired sequence. Means are provided for sensing the passage of the strip through stands S1, S2, S5 and S6. This may comprise, for example, strain gages or roll force load cells 62 and 64 on stands S1 and S2 and strain gages 67 and 69 on stands S5 and S6, respectively. The signals produced by the strain gages 62 and 64 are applied to a logic module, preferably an AND circuit 66; and assuming that the strip is in both stands S1 and S2, the AND module 66 produces an output which is inverted in inverter 68 and applied to AND logic module 70. At the same time, the output of AND module 66 is applied through a 2-second delay circuit 72, inverted in inverter 74, and applied to the AND logic module 70. Between the time that the strip enters the stand S2 and the time delay period of circuit 72, the AND module 70 produces an output which is applied through logic modules 76 and 78 and lead 80 to the relay CR4, thereby energizing this relay and closing its contacts CR4-A.

When the strip is in stands S1 and S2, the signals from strain gages 62 and 64 are applied to AND logic module 82 which, through inverter 84, causes a flip-flop circuit 86 to reverse its stable states of conduction. In one stable state of conduction, AND logic module 88 is activated; whereas, in the other stable state of conduction, AND logic module 90 is activated. Assum-

ing that AND logic module 88 is activated, the output of AND module 70 persisting for 2 seconds when the strip enters the second stand S2 causes an output signal from AND module 88 to pass through inverters 92 and 94 to momentarily energize, through leads 96 and 98, the relays CR2 and CR3. Under these circumstances, the temperature signal from the previous workpiece stored in integrator 26 is compared with that from the workpiece then passing through the mill; and at the same time the temperature from the workpiece passing through the mill is stored in integrator 24.

When the next successive workpiece passes through stand S1 and enters stand S2, the flip-flop 86 will reverse its stable states of conduction, thereby activating the AND logic module 90. Now, when the two-second signal appears at the output of module 70, and the AND logic module 88 will block the signal; however the module 90 will pass it to two inverters 100 and 102. The output of inverter 100 is utilized via lead 104 to energize relay CR5; whereas the output of module 102 is applied via lead 106 to energize the relay CR1. Thus, on this succeeding workpiece, relays CR1 and CR5 are energized momentarily for about 2 seconds; whereas relays CR2 and CR3 remain deenergized. The relay CR4, of course, is always energized upon passage of each workpiece through the mill.

The strain gages 67 and 69 sense the passage of the trailing end of the workpiece through the mill. Signals indicating the passage of the workpiece through the mill are applied to a logic circuit 108 including a signal memory function such as the charging of a capacitor to block the circuit and which will produce an output signal on lead 110, assuming that no preceding workpiece has passed through the mill in a period of 3 to 4 minutes. Under these circumstances, AND logic module 112, upon receipt of the 2-second signal from module 70, will produce a signal which is inverted in inverter 114 and applied to relay CR6 which closes its contacts CR6-A to reset the screwdown control circuit 14. This is for the reason that in the 3 to 4 minute delay interval, the signal proportional to temperature stored in the integrator 24 or 26 has been dissipated. Consequently, any attempt to compare actual temperature with the stored temperature would give erroneous measurements.

The present invention thus provides a means for measuring the temperatures of successive workpieces rolled on a hot rolling mill and for changing the screwdown setting of the mill based upon a comparison of the temperature of a workpiece measured and that of a previous workpiece, this comparison preferably being taken in combination with a measurement of the gage of the previous workpiece. Although the invention has been shown in connection with a specific embodiment, it will be readily apparent to those skilled in the art that various changes in form and arrangement of parts may be made to suit requirements without departing from the spirit and scope of the invention.

I claim as my invention:

1. In a rolling mill workpiece gage control system, the combination of signal producing means for producing respective electrical signals proportional to the temperature of the forward ends of successive workpieces passing through the rolling mill, storage means for storing each of said electrical signals for a predeter-

mined time period related to the passage of said workpieces, comparison means operable when the temperature of the forward end of a given workpiece is measured within said time period for comparing the signal proportional to the temperature of said given workpiece with the signal proportional to the temperature of a preceding workpiece to produce an error signal related to a predetermined comparison of said signals, and control means responsive to said error signal for controlling said workpiece gage, said storage means for storing said electrical signals comprises a pair of integrators, first switch means actuatable when a workpiece passes through said mill for connecting one of said integrators to said signal producing means while connecting the other integrator to said comparison means, and second switch means actuatable when the next successive workpiece passes through said mill for connecting the other of said integrators to said signal producing means while connecting said one integrator to said comparison.

2. The control system of claim 1 wherein said rolling mill comprises a tandem mill having a plurality of rolling stands, means for sensing passage of the forward end of a workpiece through the second of said stands, means responsive to said sensing means upon passage of a workpiece through the second stand for closing said first switch means while maintaining said second switch means open, and means responsive to said sensing means for closing said second switch means while maintaining the first switch means open upon passage of the next successive workpiece through said second stand.

3. The control system of claim 2 including switch means actuatable when the forward end of a workpiece is in said second stand for connecting said signal producing means to said comparison means.

4. The control system of claim 3 wherein each of said switch means is closed momentarily only after a workpiece passes through said first stand and enters the second stand.

5. The control system of claim 4 including means for sensing the passage of the trailing end of a workpiece through the last stand of said tandem rolling mill and means responsive to said last-named sensing means and actuatable after a predetermined time delay for controlling said workpiece gage by resetting the screwdown control system for said rolling mill.

6. The control system of claim 1 including means for producing an electrical signal which varies as a function of the gage of the forward end of a workpiece emerging from said mill, means for storing said electrical signal which varies as a function of gage, said means for comparing signals including means for comparing said temperature-proportional signals with said stored electrical signal which varies as a function of gage.

7. The control system of claim 6 wherein the latter said stored electrical signal is proportional to the gage of the forward end of a workpiece which has passed through the mill immediately preceding the workpiece passing through the mill during a comparison made by the latter said signal comparing means.

8. The control system of claim 1 wherein said rolling mill comprises a tandem mill having a plurality of rolling stands, with said signal producing means being disposed between the first and second stands.
